SHEET METAL WORKING DEVICE

Roy Lee Hollaway, San Francisco, Calif., assignor
of thirty per cent to Manfred M. Warren, Oak-
land, Calif.

Application June 18, 1949, Serial No. 100,070

7 Claims. (Cl. 153—32)

1

The invention relates to machines and tools for straightening or otherwise working into desired form of sheet metal or the like.

An object of the present invention is to provide a sheet metal working device of the character described which is broadly adaptable for working a wide variety of shapes and forms of sheet metal having dented or damaged contours, for the purpose of restoring such forms to their original flat or curved configuration, as the case may be.

Another object of the invention is to provide a device of the character above which obviates the customary pounding or hammering of the material being worked, with its attendant severe noise and hammered indentations and stretching of the material, and substitutes in its stead a rolling and working action which is rapid and quiet and functions to flow the material into its original contour, thereby restoring the surface to a smooth finish substantially free from indentations, ripples or other surface distortion.

A further object of the invention is to provide a sheet metal working device of the character described which is readily portable and easily and quickly applied to various sheet metal parts to be worked such as fender and body portions of an automobile, and which is conveniently powered by a source of compressed air customarily found in garages, body shops, and the like.

Still another object of the present invention is to provide a device of the character above which may be easily handled and efficiently and properly operated by a workman with a minimum of training, and is fully adjustable and quickly responsive in the hands of the operator in the course of operation of the machine over adjacent portions of the sheet metal being worked wherein the several portions have various types of damage or distortion.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a side elevation, shown partly in section, of a sheet metal working device constructed in accordance with the present invention.

Figure 2 is a fragmentary cross-sectional view on an enlarged scale of a portion of the device illustrated in Figure 1.

2

Figure 3 is a fragmentary cross-sectional view of the device taken substantially on the plane of line 3—3 of Figure 3.

The sheet metal working device of the present invention consists, briefly, in the combination of a work-holding element and roller arranged for clamping on the opposite sides of sheet metal to be worked with the periphery of the roller positioned against the work and wherein the roller is journaled for rotation about its longitudinal axis so as to roll upon the work surface. In this manner, dents, creases and other surface distortions are rolled and worked out so as to restore the sheet to its original contour.

With reference more specifically to the accompanying drawing, the device preferably utilizes a plurality of such rollers here arranged in roller assembly 6 which is supported at one end 7 of a frame 8 in generally opposed relation to a work-holding element 9 carried at an opposite end 11 of the frame. The frame as illustrated in Figure 1 is preferably of open, generally C-shaped form so as to permit a ready positioning of the roller assembly 6 and the work-holding element 9 on opposite sides of the sheet metal to be worked and at a position somewhat removed interiorly from an edge of the material.

The roller assembly 6 preferably consists of a pair of rollers 12 and 13 desirably of identical form and diameter journaled for rotation in coaxial relation on a common shaft 14 and held in axially spaced relation by a sleeve 16 mounted on the shaft 14 between the rollers 12 and 13. The rollers thus supported are carried for rotation in the plane of their common axis by the mounting of the opposite ends of the shaft 14 in the spaced legs 17 and 18 of a clevis-type bracket 20 having a side 19 connecting the legs 17 and 18 and secured to the drive shaft 21 of a motor 22, the shaft 21 being connected to the bracket centrally between the legs 17 and 18, with the axis of rotation of the unit substantially intersecting the axis of the shaft 14 and passing approximately midway between the rollers 12 and 13.

Any suitable motive power may be used for driving the roller assembly. Desirably, due to the requirement for sometimes positioning the motor ahead of the unit in a relatively restricted space, the motor should be kept as small as is consistent with needed power. A conventional-type air motor is very satisfactory for this purpose and may be obtained in small sizes having sufficient power for the purposes here required. Since such air motors are widely used in the art and their construction well known, no detail of construction is shown in the drawing.

In various types of metal straightening, such as encountered in automotive fender and body work, it is desirable to provide a plurality of frames of different sizes affording differences in

the positioning of the operating heads of the tool. For this reason, the motor and roller assembly unit is preferably detachably secured to the frame end 7. Such construction is here effected by maintaining the motor within a casing 23 which is in turn fastened to a sleeve 24 detachably and telescopically mounted over the frame end 7. Pins 26 may be used to hold the unit in assembled position on the frame end 7. Motive power for the air motor 22 is usually conveniently obtained from a compressed air source, in a garage, body shop, or the like. As here shown, an air inlet conduit 27 is provided with a branch conduit 28 which leads to the motor 22, a manually controllable air valve 29 being preferably inserted in the line near the motor. Also, since it is desirable to detach the motor for connection to other frames, a detachable pipe connection 31, is preferably provided in the branch line 28.

As a feature of the motor head construction, the casing 23 is preferably extended from the motor 22 so as to also enclose the motor shaft 21 and a portion of the roller assembly. In this manner, only approximately half of the diameter of the rollers 12 and 13 projects from the open end of the casing, and the casing thus serves as a guard to prevent the striking of the bracket and the rollers against proximately located objects during the rotation of the roller assembly.

The work-supporting element 9 is also preferably of roller construction and includes an assembly of a plurality of rollers 32 of identical form and diameter mounted in side by side relation and journalled for rotation on a common shaft 33. This assembly of rollers, like the first roller assembly, is supported for rotation about an axis perpendicular to the axis of the shaft 33. As will be seen from the drawings, the opposite ends of shaft 33 are mounted in spaced legs 34 and 36 of a clevis-type bracket 37 having a connecting side 38 fixed to a shaft 39, the shaft being attached to the side 38 substantially midway between the bracket ends 34 and 36 and having an axis substantially perpendicular to and intersecting the axis of shaft 33.

When not in use, the roller assemblies 6 and 9 are normally retained in spaced opposed position as illustrated in Figure 1 of the drawing, so as to permit the ready positioning of these opposed units on opposite sides of the sheet metal to be worked. Means is provided for moving the units together to clamp them on opposite sides of the portions of sheet metal 40 to be worked, such as illustrated in Figures 2 and 3. As a feature of the present construction, this clamping means provides a resilient, yieldable pressure of the roller assemblies on the work so as to most effectively iron out indentations, creases or other deformities. The function of displacing one of the units to obtain a clamping of the material between the units and the resilient and yieldable pressure applied to the material is here obtained by the mounting of the work supporting element 9 upon a pneumatic actuator 41 carried on the end 11 of the frame. As here shown, the actuator comprises a casing 42 affording an interior air cylinder 43 within which is mounted for reciprocation a piston 44. The cylinder 43, is provided with a head end 46 having an air opening 47 leading to the cylinder and fitted exteriorly with a connector 48 having an air supply line 49 here carried within the frame 8 and extending out of the frame adjacent to the opposite end for connection to a conduit 51, in turn connected to the supply conduit 27. A manually controllable air valve 52 is desirably provided in the line 51.

The piston 44 is preferably fitted with a conventional-type cup washer 53 at its lower end and is retained within the opposite end of the cylinder by a collar 54 threaded onto such cylinder end and fitted about the piston. A washer 56 carried on the lower end of the piston is arranged for engagement with the collar 54 to limit the outward displacement of the piston from the cylinder.

Preferably, the pneumatic actuator is also detachably secured to the frame and as here shown the casing 42 is provided with a depending threaded skirt 57 which may be threadably attached to and detached from the frame end 11.

Preferably, the work-engaging element 9 is carried by the pneumatic piston 44 at the outer end 58 of the piston. As here shown, the piston is provided with an end bore 59, see Figure 2, for receiving and journaling for rotation the bracket shaft 39. An anti-friction thrust bearing 61 is desirably positioned between the end 58 of the piston and the bracket side 38. A set screw 62 may be provided adjacent the outer end of the piston and entering a peripheral recess 63 in the shaft 39 for retaining the work-supporting element in connected position on the piston.

In starting to use the device, the valve 52 will be closed and the piston 44 and work-supporting element 9 retracted into spaced relation from the roller assembly 6 as illustrated in Figure 1, it being noted that when the valve 52 is closed the piston may be manually inserted into the cylinder 43. The device may then be positioned to locate the opposed roller assemblies on opposite sides of the damaged portion of sheet metal to be worked. Thereupon, the valve 52 is opened to eject the air piston 44 and firmly clamp the work between the roller assemblies 6 and 9. Since the ejection of piston 44 is rapid and accompanied by considerable force, the initial impact of the work-supporting element 9 may be utilized as an air jack or air hammer so as to obtain a desired deflection of the sheet metal. As will be understood, when the sheet metal portion to be worked has been thus clamped between the roller assemblies, valve 29 is opened so as to initiate rotation of the roller assembly 6. By reason of the construction above described, the rollers 12 and 13 of this assembly are caused to traverse a circular pattern during the course of which the rollers forcibly bear and roll upon the work. At the same time, the opposite roller assembly 9 is free to swivel and will constantly and automatically orient itself to press out protuberances on its side of the sheet metal and to also afford maximum work support for the roller assembly 6 being power-driven at the opposite side. This combination is highly effective in rolling, pressing and otherwise working the material into its original contour and leaving the work surfaces very smooth and substantially free from indentations, ripples and other distortions. By easy manipulation of the operator the device may be used to restore surfaces of substantially any of a wide variety of shapes from flat to rounded contours. Of importance is the fact that the damaged portions are quickly worked into their smooth original contour without any noticeable stretching of the metal. Since the device does not function by hammering or pounding on the metal, the very severe noise attendant on the use of a conventional air hammer or the like is completely obviated.

I claim:

1. A sheet metal working device comprising,

a pair of rollers, means journaling said rollers for rotation about their axes and supporting the peripheries of said rollers in opposed substantially parallel planes, means for clamping said roller peripheries on opposite sides of sheet metal to be worked, means for rotating one of said first-named roller supporting means and the roller carried thereby about an axis substantially perpendicular to said roller axis, the other of said roller supporting means being supported to freely swivel about an axis substantially perpendicular to the axis of the roller carried thereby.

2. A sheet metal working device comprising, a roller assembly including a pair of axially aligned and axially spaced rollers journalled for rotation about their common axis, a third roller, mounting means journaling said third roller for rotation about its axis and positioning the periphery of said third roller in opposed substantially parallel relation to the peripheries of said first-named rollers, means resiliently clamping the peripheries of said first-named rollers and said third roller periphery on opposite sides of sheet metal to be worked, power motive means for rotating said roller assembly about an axis substantially perpendicular to said common roller axis and located between said first named rollers, said mounting means for said third roller being formed to freely swivel about an axis substantially perpendicular to said third roller axis and substantially aligned with said axis of rotation of said roller assembly.

3. A sheet metal working device comprising, a roller assembly including a pair of axially aligned and axially spaced rollers journalled for rotation about their common axis, a second roller assembly including a plurality of side by side axially aligned rollers journalled for rotation about their common axis, mounting means for said roller assemblies positioning said common axes in spaced parallel planes and for resiliently clamping sheet metal to be worked between the opposed roller peripheries, power motive means for rotating said first named roller assembly about an axis substantially perpendicular to said first named common roller axis and mounted between said spaced rollers of said assembly, said mounting means for said second assembly being formed to permit a free swiveling action of said second roller assembly about an axis substantially perpendicular to said common axis of the rollers thereof and substantially aligned with the said axis of rotation of said first named roller assembly.

4. A sheet metal working device comprising, a pair of rollers mounted in side by side relation and supported for rotation about axes in spaced parallel planes, means for resiliently clamping the opposed peripheries of said rollers on opposite sides of sheet metal to be worked and including a pneumatically operated piston for urging one of said rollers in the direction of the other roller, the supporting means for said rollers being journalled for rotation about substantially aligned axes perpendicular to said roller axes, and motor means for continuous, high speed rotation of one of said roller supporting means about its said axis of rotation, the other roller supporting means being free to swivel about its axis of rotation.

5. A sheet metal working device comprising, a substantially C-shaped frame having spaced ends in generally opposed position, an air motor

carried by one of said ends and having a drive shaft extending in the direction of said other end, a roller assembly mounted on said shaft for rotation therewith and including a pair of axially aligned and axially spaced rollers journalled for rotation about their common axis substantially perpendicular to the axis of said shaft and arranged with said shaft axis extending between said rollers, a pneumatically operated piston carried by said other frame end and extendable therefrom in the direction of said roller assembly, and a second roller assembly carried by said piston and journalled for rotation about an axis substantially aligned with the axis of extension of said piston and including a plurality of aligned rollers journalled for rotation about their common axis arranged substantially perpendicular to the axis of rotation of said second assembly.

20 6. A sheet metal working device comprising, a substantially C-shaped frame having spaced ends in generally opposed position, a motor carried by one of said ends and having a rotary drive shaft extending therefrom in the direction of said other end, a roller assembly mounted on said shaft for rotation therewith and including a pair of axially aligned and axially spaced rollers journalled for rotation about their common axis substantially perpendicular to the axis of said shaft, a work supporting member carried by the other end of said frame in opposed relation to the peripheries of said rollers, and means for resiliently clamping said roller peripheries and said work supporting member on opposite sides of sheet metal to be worked.

35 7. A sheet metal working device comprising, a substantially C-shaped frame having spaced ends in generally opposed position, a motor carried by one of said ends and having a rotary drive shaft extending therefrom in the direction of said other end, a roller assembly mounted on said shaft for rotation therewith and including a pair of axially aligned and axially spaced rollers journalled for rotation about their common axis substantially perpendicular to the axis of said shaft, a hollow casing extending from said motor concentric to said drive shaft and having an open end surrounding said roller assembly, a work supporting member carried by the other end of said frame in opposed relation to the peripheries of said rollers, and means for resiliently clamping said roller peripheries and said work supporting member on opposite sides of sheet metal to be worked.
